UNITED STATES PATENT OFFICE.

GEORGE G. THIBEDEAU, OF PORTLAND, MAINE.

CLOTHES DRIER.

Application filed November 17, 1921. Serial No. 515,796.

To all whom it may concern:

Be it known that I, GEORGE G. THIBEDEAU, a citizen of the United States, residing at Portland, in the county of Cumberland and 5 State of Maine, have invented certain new and useful Improvements in Clothes Driers, of which the following is a specification.

My invention relates to that class of clothes driers adapted to be secured to the 10 kitchen wall and to be held at different elevations so that the drier may be located at a convenient low level and then lifted into a relatively high position or at the top of the room which is the hottest place.

15 My invention is directed first to the construction of a simple and practical vertical guide or runway and an arm supporting bracket of novel construction adapted to slide on said guide and second to simple 20 means for holding the drier at the proper elevation and arranged to be quickly released and automatically locked.

25 The novel features of my invention will be specifically pointed out in the appended claim.

I have illustrated my invention in the accompanying drawing in which:

Fig. 1 is a side elevation of the clothes 30 dryer a portion of the bracket being shown in section.

Fig. 2 is a plan, with one of the drying arms in its drying position,

Fig. 3 is a section on the line 3—3 of 35 Fig. 4,

Fig. 4 is a section on the line 4—4 of Fig. 3 and,

Fig. 5 is a front elevation of a portion of the bracket.

In the drawing, similar letters of reference indicate similar parts.

40 My dryer is supported on a vertically movable slide 1 preferably made of sheet metal with flanges 2 which fit into grooves 3 formed in opposite edges of a guide strip 4 adapted to be secured to the wall of the kitchen or other department where the drier 45 is to be utilized.

The drying bars 8 are held by a bracket 5 preferably formed of cast iron and secured by screws or otherwise to the front 50 face of the slide 1. The bracket 5 is provided with a central web 7 semi-circular in form with a series of radial arms 6 extending outward therefrom.

55 The drying bars 8 are disposed between the radial arms 6 and are held in place by

a pivoting wire 9 passing through the arms 6 and the longitudinal slot 10 formed in the bars 8. The bracket casting 5 is formed with a ledge 11 which extends around parallel with the wire 9 and somewhat below the arms 6 so that when the bar 8 is in a horizontal position, the upper surface of its inner end will rest immediately beneath the web 7 and the lower edge of the arm 65 will rest on the top of the ledge 11.

60 By pulling the arm outward while in its horizontal position, until the inner end of the slot 10 comes against the wire 9, the arm will hang down in a perpendicular position and will remain there while not in use.

65 Means are provided for raising and lowering the bracket and securing it in any desired location. For this purpose, I make 70 use of a rod 13 having at its lower end a handle 14 for lifting and lowering the bracket 5, the upper end of the rod being firmly secured to the bracket. Secured to the lower end of the guide 4 is a locking device 75 consisting of the hollow casing or socket 15 having opposing flanges with a vertical opening through which the rod 13 passes and which act as a guide for the rod.

80 A locking lever or catch 16 for checking 85 the rod 13 at any desired elevation is pivoted inside of the casing to the ears 17. The locking lever 16 has an opening through which the rod 13 passes with a loose fit so that when the lever 16 is depressed slightly 90 from a horizontal position, it creates a pinch on the rod and holds up the rod and the bracket in any desired position.

When the lever 16 is lifted so as to bring it at right angles to the rod, the latter slides 95 freely through it but when the lever is depressed or pressed downward, the pinch takes place on the rod 13 and the latter is held firmly.

100 In order to make sure that the locking lever when released will always pinch the rod, I provide a spiral spring 18 which surrounds the rod 13 and presses down on the lever 16 contacting with the inner surface of the casing 15.

105 Thus, when the lever 16 is raised slightly by the hand, the rod 13 may be pushed up or allowed to fall until the bracket 5 is in any desired position and when the lever is released, the spring 18 forces it down 110 at once and serves to lock it in place.

When the bracket is to be raised it is

only necessary to lift the rod or force it upwards without manipulating the lever as the rod will stay in any position without further manipulation of the other parts.

5 A clothes drier constructed as I have described may be quickly lowered to receive the clothes and quickly raised to a high position in the room and the drying arms may be all used or a few of them used according to circumstances.

I claim:—

In a clothes drier, the combination of a

vertical guide; a slide mounted thereon, a bracket secured to said slide, a lifting rod to raise and lower the bracket, a hollow casing having a vertical opening there-through for the passage of said rod, a catch having an opening for the passage of said rod slightly larger than the rod pivotally connected at its inner end to said hollow casing and a spiral spring for holding said catch downward and in a locking position.

GEORGE G. THIBEDEAU.
